UNITED STATES PATENT OFFICE.

ISADOR DICHTER, OF CHICAGO, ILLINOIS.

DESIGN FOR A FLOOR-LAMP STAND.

Application filed January 15, 1926. Serial No. 16,102. Term of patent $3\frac{1}{2}$ years.

To all whom it may concern:

Be it known that I, ISADOR DICHTER, a citizen of the United States, residing at Chicago, in the county of Cook and State of Illinois, have invented a new, original, and ornamental Design for Floor-Lamp Stands, of which the following is a specification, reference being had to the accompanying drawing, forming part thereof.

The figure is a perspective view of a floor lamp stand showing my new design.

I claim:

The ornamental design for a floor lamp stand, as shown.

In testimony whereof I affix my signature at 10 South La Salle Street, Otis Building, Chicago, Illinois.

ISADOR DICHTER.
